UNITED STATES PATENT OFFICE.

WILLIAM PARKIN, OF TAUNTON, MASSACHUSETTS, ASSIGNOR TO REED & BARTON, OF SAME PLACE.

DESIGN FOR COFFIN-PLATES.

Specification forming part of Design No. 7,114, dated May 5, 1874; application filed March 31, 1874.
[Term of Patent 7 years.]

CASE B.

To all whom it may concern:

Be it known that I, WILLIAM PARKIN, of Taunton, in the county of Bristol and State of Massachusetts, have invented a Design for Coffin-Plates, of which the following is a specification:

The invention relates to coffin-plates; and consists in a design therefor, as hereinafter fully described, and subsequently pointed out in the claim.

The figure represents a plan view of my invention.

A represents a raised middle surface for the superscription, having a rectangular outline, *a*, and made plain on its face. Around the line of demarcation *a* is formed a broad and elevated perimeter, C, or border, enlarged and extended at the corners *c' c'*, and on the up-

per surface ornamented with figures or floral decorations. About the middle of the upper side is formed the hollow vase or bouquet-holder G, and from the lower side hang the pointed pendants H. These unite to present to the beholder a very attractive and ornamental entirety.

What I claim as my invention is—

1. A new design in coffin-plates, consisting of rectangular plain surface A, ornamental border C, and vase G, arranged as shown and described.

2. The pendants H on the lower edge of a coffin-plate, as shown and described.

WILLIAM PARKIN.
